UNITED STATES PATENT OFFICE.

GEORGE E. MOLYNEUX, OF BAYONNE, NEW JERSEY, ASSIGNOR TO THE SINGER MANUFACTURING COMPANY, A CORPORATION OF NEW JERSEY.

FEEDING MECHANISM FOR SEWING-MACHINES.

1,191,089.

Specification of Letters Patent. Patented July 11, 1916.

Application filed January 26, 1914. Serial No. 814,291.

To all whom it may concern:

Be it known that I, GEORGE E. MOLYNEUX, a citizen of the United States, residing at Bayonne, in the county of Hudson and State of New Jersey, have invented certain new and useful Improvements in Feeding Mechanisms for Sewing-Machines, of which the following is a specification, reference being had therein to the accompanying drawings.

This invention has for its object to provide a simple, strong and effective feeding mechanism for sewing machines, and more particularly for sewing machines of that type employing a tubular work-supporting arm upon which the work is caused to travel lengthwise in the stitching operation.

In its preferred form, the invention comprises a feed-bar extending longitudinally of the work-supporting arm and having a yoke or strap rigidly connected therewith and embracing the feed-actuating eccentric upon the main-shaft by which one end of the feed-bar is confined to a fixed path of movement including its endwise operative or feeding movement, in conjunction with lifting means disposed within said arm and having an independent connection with said shaft. By this means, the feed-bar derives its endwise or work-advancing movements directly from the main-shaft which affords a support for its adjacent end, a second support near the feed-dog mounted thereon imparting to it its rising and falling movements. The lifting means are preferably connected with the feed-bar at a fixed distance from the main-shaft and by means of a sliding and pivotal joint, so that the feeding and rising and falling movements are entirely independent of each other.

In the accompanying drawings, Figure 1 is a sectional side elevation of a cylinder-bed sewing machine of the well known Singer type embodying the present improvements, and Fig. 2 a sectional plan of the hollow standard and tubular work-supporting arm with the parts contained therein. Fig. 3 is a perspective view of the feeding mechanism and certain other operative parts, detached.

The frame is composed of the usual hollow standard 1 to which is secured by screws 2 the end flange 3 of the tubular work-supporting arm or horn 4, the standard having

extended from its upper end the overhanging tubular members 5 terminating in the hollow head 6. Journaled within and crosswise of the standard 1 of the arm 4 is the main-shaft 7 which is provided with the needle-actuating crank 8, thread-controller 60 actuating eccentric 9, looper rock-shaft actuating eccentrics 10 and 11, feed-actuating eccentric 12 and feed-lift eccentric 13.

The needle-bar 14 carrying the needle 15 derives its operative movements from the crank 8 through the pitman 16, crank-arm 17 on the rock-shaft 18 and crank-arm 19 on said rock-shaft connected with the needle-bar by means of the link 20 in a manner well known. The looper-carrier 21 carrying the looper 22 is pivotally mounted upon the looper-supporting rock-shaft 23 journaled within and axially of the work-supporting arm 4 and deriving its rocking movements from the eccentric 10, through the eccentric 75 rod 24, plural-armed rocker 25 and link connection 26 with the crank 27 upon said rock-shaft, as shown and described more fully in my Patent No. 1,127,069, issued February 2, 1915. The sidewise movements of the looper 80 are derived from the eccentric 11 through the eccentric rod 28 pivotally connected with the endwise movable bar 29 journaled within the arm 4 beneath the looper-supporting rock-shaft and having a sliding and 85 pivotal connection with the looper-carrier similarly to that of my said patent.

As represented in the drawings, the feed-bar 30 has secured upon its threaded rearward end the split yoke or strap 31 embracing the feed-actuating eccentric 12 and deriving therefrom circular movements in a fixed path, which movements are communicated to the adjacent end of the feed-bar in operative endwise or work-advancing movements and transverse movements. The feed-bar extends within and lengthwise of the arm 4 above the looper rock-shaft 23 and has secured upon its forward portion by means of the set-screws 32 the suitably socketed 100 end of a block 33 of angular cross-section fitted to and guided within a guideway formed in the top of the bearing member 4' in the forward end of the arm 4. The block 33 has in its upper face the countersunk 105 seat 34 upon which is adjustably secured by means of the fastening screw 35 the slotted foot 36 of the feed-dog 37 whose serrated

operative portions are adapted to extend through the usual apertures in the throat-plate 38.

The block 33, constituting the forward portion of the feed-bar, is shown formed with a transverse rectangular slideway 39 arranged lengthwise thereof in which is fitted the slide-block 40 pivotally sustained by the screw-pin 41 between the spaced lugs 10 42 of the forked arm 43 of a rock-lever having its apertured hubs 44 entered by the transverse journal-pins 45 tapped into the arm 4 and provided with a rearwardly extending arm 46. The rearward end of the 15 rock-lever arm 46 carries a stud-pin 47 embraced by the apertured end of the rod 48 provided with the eccentric strap 49 embracing the feed-lift eccentric 13.

The means employed in connection with 20 the present improvement for adjusting the throw of the feed-actuating eccentric is preferably that of my Patent No. 1,146,437, issued July 13, 1915, the eccentric being controlled in its lateral position upon the shaft 25 by means of the peripherally notched disk member 50.

By the use of a crank or eccentric upon the main-shaft embraced by a strap having a rigid connection with the feed-bar, a peripherally continuous bearing contact is produced 30 between the operative parts which provides ample bearing surface to insure durability and to exclude grit or other injurious matter, while the feed-bar receives therefrom endwise reciprocating movements whose gradual reversal is free from shock owing to the circular movement of which it is one of the component elements, thereby preventing the noise produced with certain 35 other types of feed actuation. Owing to the pivotal support of the feed-bar within the work-supporting arm at a point near the opposite end of the feed-bar, the crosswise movement of the latter derived from the 40 feed-actuating eccentric is so slight in its effect upon the feed-dog as to be negligible, while the connection of the lifting means with the feed-bar is sufficiently close to the feed-dog to prevent the appreciable springing 45 of the feed-bar under the action of the 50

strongest pressures applied by the pressure spring 51 to the presser-foot 52 through the presser-bar 53. This relation of the parts permits the employment of independent means for imparting endwise feeding and 55 rising and falling movements to the feed-bar, so that adjustments may be made in the length of feed without appreciably affecting the amplitude of the vertical movements of the feed-dog.

It is obvious that the present improvement, while designed especially for the "cylinder-bed" type of machines, is adapted for other types, and that the construction and arrangement of its component elements may 60 be considerably varied within the scope of the present invention.

Having thus set forth the nature of the invention, what I claim herein is:—

In a sewing machine, the combination with 70 the frame comprising a hollow standard and a tubular work-supporting arm extending laterally therefrom, of a rotary shaft mounted within said standard and transversely thereof and of said work-supporting arm, feed-actuating and-lifting eccentric elements upon said shaft, a feed-bar extending through said arm and having at one end a strap embracing the feed-actuating eccentric element, a feed-dog mounted upon the opposite end of said feed-bar, a rock-lever mounted upon a fixed fulcrum within and transverse to said work-supporting arm, and having an arm extending lengthwise of 75 said feed-bar, a rectilinearly sliding connection between said arm of the rock-lever and the feed-bar and disposed intermediate said transverse fulcrum and the feed-dog, and a link connection within said standard at one end with another arm of said rock-lever and 80 provided at the opposite end with a strap 85 embracing the feed-lifting eccentric.

In testimony whereof, I have signed my name to this specification, in the presence of two subscribing witnesses.

GEORGE E. MOLYNEUX.
